TRUSS END CONSTRUCTION

Axel V. Pedersen, Los Angeles, Calif.

Application July 3, 1947; Serial No. 758,757

2 Claims. (Cl. 20—0.5)

1
This invention relates to improvements in truss end constructions. The conventional wooden truss used in the construction of buildings has a curved upper chord in which compression stresses are developed and a horizontal lower chord in which tension stresses are developed. Heretofore metal shoes have frequently been employed to form a connection between the ends of the upper chord and the ends of the lower chord. These shoes, while satisfactory, have the objection that they are sometimes difficult to fit in transmitting the compressive stresses from the upper chord to the lower chord so that the lower chord may properly perform its function of resisting spreading of the ends of the upper chord.

In the manufacturing of trusses of this type the upper chord is usually made up of laminations and there frequently is a considerable amount of scrap material available in cutting and positioning the laminations of the upper chord so that they have staggered joints.

An object of the present invention is to provide an improved truss end construction which is highly advantageous in that it enables a proper transfer of stresses from the upper chord to the lower chord and which will enable the utilization of a substantial portion of lamination scrap that would otherwise be wasted.

Another object of the invention is to provide a truss end construction which will enable a satisfactory connection to be made between the curved upper chord and the horizontal lower chord even though the upper chord may be materially wider than the lower chord. In many truss designs the materials employed are such that the lower chord need not be as wide or as thick as the upper chord and in order to most advantageously employ the material used it is desirable to have the lower chord of smaller dimensions than the upper chord. Particularly is this true where weight of the entire truss is an important factor. The improved truss end construction enables the use of such chords and provides an excellent connection therebetween.

With the foregoing and other objects in view, which will be made manifest in the following detailed description and specifically pointed out in the appended claims, reference is had to the accompanying drawings for an illustrative embodiment of the invention, wherein:

Figure 1 is a view in side elevation of the end of a truss embodying the present invention;

Figs. 2 and 3 are partial views in elevation taken substantially upon the lines 2—2 and 3—3, respectively, upon Fig. 1 in the direction indicated; and

2
Fig. 4 is a view in side elevation of a modified or alternate form of construction embodying the present invention.

Referring to the accompanying drawings wherein similar reference characters designate similar parts throughout, 10 indicates the end of a curved upper chord of a wooden truss. 11 indicates the end of the horizontal chord of the truss. In accordance with common practice the curved upper chord 10 is made up of a series of wooden laminations that are glued together and which collectively are bent to the desired curve of the upper chord. The lower chord 11 may be but ordinarily is not laminated. In the course of construction of the truss there frequently develops a number of short pieces of laminations which heretofore have either been wasted or employed in a manner that is not particularly useful. In accordance with the present invention these laminations are utilized to provide the connection between the end of the upper chord 10 and the end of the lower chord 11. In so doing the laminations are trimmed along their faces so as to be tapered as indicated at 12. These 25 tapered laminations then have their abutting faces glued together so that the glue planes or planes of adhesion between adjacent laminations in effect radiate from a center located at the inner section of the axis of the end of the lower chord 11 and the axis of the end of the upper chord 10. The uppermost laminations indicated at 13 and which are disposed in planes substantially parallel to the end of the upper chord 10 need not be tapered and preferably have the 30 glue planes or adhesion planes therebetween arranged substantially parallel to the axis of the end of the upper chord. In a similar manner the lowermost laminations 14 need not be tapered and may be arranged parallel to the length of the horizontal chord 11. When the block of glue 35 laminations is thus prepared it is ready for assembly with the ends of the upper and lower chords. Any form of connection between this block and the end of the upper chord that is 40 suitable for transmitting compressive stresses from the upper chord to the block may be employed and likewise any form of connection suitable for transmitting tension stresses between the bottom of the block of laminations and the 45 end of the lower chord 11 may be employed. In the preferred form of construction, however, I 50 prefer to employ a wood joint of the type disclosed in my copending application Serial No. 516,067, filed December 29, 1943, now abandoned, 55 wherein the end of the upper chord 10 has oppositely shaped scarfs 15 and 16 formed thereon, one above the other. The slopes of these scarfs

are preferably less than 1:6 and usually are in the neighborhood of 1:10 or 1:12. In a similar manner the upper portion of the triangular laminated block is equipped with complementary scarfs indicated at 17 and 18. The end of the lower chord 11 is similarly scarfed as indicated at 19 and 20 and complementary scarfs 21 and 22 are formed on the laminated block. These opposed mutually engaging scarfed faces on the chords and on the block are glued to each other thus completing the connection between the upper chord and the lower chord. It will be noted that by this construction the glue planes or planes of adhesion between the laminations of the block gradually and progressively change in position from the horizontal, which is parallel to the horizontal bottom chord 11, to a position parallel to the end of the upper chord 10. These glue planes or planes of adhesion are thus most advantageously arranged to transmit the shear developed in the block between the compressive upper chord 10 and the horizontal lower chord 11 which is under tension. Usually the ability of the adhesive to carry shear stresses is greater than that of the wood laminations itself but as the wood laminations are relatively thin they are capable of carrying this shear stress under ordinary truss design if the thickness of the block is made equal to the thickness of the upper chord. In this way I am able to not only use lamination scraps to advantage but, by the arrangement of the glue planes, I may nicely and in a distributed manner transmit compression from the upper chord to the tensile lower chord 11.

In many forms of truss design it is desirable to utilize a thinner lower chord 11 than the upper chord 10 and to this end the lower chord 11 is shown as being considerably thinner than the block of laminations 12 in Fig. 3. With this arrangement, one side of the lower chord is disposed flush with one side of the laminated block and the scarfs cut on the laminated block to complement the scarfs on the end of the lower chord. At the end of the innermost scarf 20 on the lower chord the block may merely be shouldered as indicated at 23.

In Fig. 4 there is disclosed an alternate form of construction wherein the lamination scraps have been tapered and glued together to form a block generally indicated at 24 wherein the glue planes approximately radiate from a center at the intersection of the upper chord as extended with the lower chord as extended. In this form of construction any type of connection may be employed to transmit compressive stresses from the upper chord 25 to the block, but a double scarfed wood joint as above described has been illustrated. The lower chord 26 has its top surface positioned directly against the bottom of the laminated block and glued directly thereto. In this form of construction it is not essential to use untapered laminations corresponding to those illustrated at 13 and 14 on Fig. 1. The stress developed in the block is transmitted directly to the lower chord through the glued surfaces at 27 and immediately above the lower chord the laminations of the block may start tapering immediately. While there is a slight departure of the uppermost glue planes of the block from being exactly parallel with the end of the upper chord 25, this slight departure is ordinarily not of any great consequence. In both

forms of construction as illustrated, the glue planes between the laminations of the block are approximately parallel to the direction of shear in their respective locations.

It will be appreciated from the above described construction that the improved truss end connection is quite versatile in that it optionally enables the upper and lower chords to be either of equal thickness or of unequal thickness. Furthermore, accurate fitting of parts as in the case of a metal shoe is not required.

In the conventional wooden truss construction the laminations of the upper and lower chords are made from boards wherein the grain runs lengthwise thereof and as the laminations 12 and 24 are usually prepared from scraps from these boards they will likewise have their grains running lengthwise thereof. The trimming of these scraps or pieces to taper them does not alter or affect their grain arrangement with relation to the lengths of the laminations. Consequently when the tapered laminations are stacked together the grains of the laminations will be running lengthwise substantially parallel to the glue planes between adjacent laminations.

Various changes may be made in the details of construction without departing from the spirit and scope of the invention as defined by the appended claims.

I claim:

1. A wooden truss having a horizontal lower chord and a curved upper chord, the ends of the chords being adjacent each other and arranged so that their axes if projected would intersect each other at an angle, a stack of tapered wooden laminations between the chord ends glued to each other and to the chords, said laminations having their grains running lengthwise thereof, the tapers of the laminations being substantially uniform toward the apex of said angle whereby the glue planes between adjacent laminations progressively change from substantially horizontal near the end of the lower chord to an inclined position near the upper chord substantially parallel to the end of the upper chord.

2. A wooden truss having a horizontal lower chord and a curved upper chord, the ends of the chords being adjacent each other and arranged so that their axes if projected would intersect each other at an angle, a stack of tapered wooden laminations between the chord ends glued to each other and to the chords, said laminations having their grains running lengthwise thereof, the tapers of the laminations being substantially uniform toward the apex of said angle whereby the glue planes between adjacent laminations progressively change from substantially horizontal near the end of the lower chord to an inclined position near the upper chord, each chord having a scarfed joint with the stack of laminations in the form of opposed scarfs on each the chord and lamination stack, which extend across a vertical plane through the stack.
